(74) Attorney, Agent, or Firm—Dennis L. Cook, Esq.

(57) **CLAIM**

The ornamental design for a V-blade cutting apparatus, as shown and described.

DESCRIPTION

FIG. 1 is a side view of the V-blade cutting apparatus showing my new design.

FIG. 2 is an enlarged side view of the claimed design disassembled;

FIG. 3 is a longitudinal view looking at the bottom surface of the blade portion;

FIG. 4 is a longitudinal view looking at the top surface of the blade portion; and,

FIG. 5 is an opposite side view of the blade portion.
The elements of the claimed design are shown detached for ease of illustration.
